UNITED STATES PATENT OFFICE.

WILLIAM B. STOUT, OF DETROIT, MICHIGAN.

GASOLINE TANK.

Application filed February 20, 1925. Serial No. 10,541.

This invention relates to gasoline tanks such as are required for the storage of gasoline in aeroplanes, and wherein it is required that means be provided in the form of splash 5 plates for the purpose of preventing undue wave action or splashing of the gasoline from end to end or from side to side of the tank when it is subjected to such vibrations or motions as would ordinarily result in such 10 wave or splashing action.

Hitherto great difficulty has been experienced in securing a comparatively flat tank of light construction capable of effectively 15 withstanding internal pressure, particularly when such tank has been required to also withstand the vibration and strains such as are met with in aeroplane practice; and it is an object of this invention to provide a tank which will meet these conditions in an 20 efficient manner without necessitating the weight usually associated with robust construction ordinarily required to secure adequate strength, or the use of rivets or similar connecting means between the shell or 25 body and the internal supporting structure.

The invention also has as its objective the provision of a splash plate structure coordinating with the structure of the tank in a manner assisting in the strengthening 30 of the same to resist pressures and strains as required, and also effecting a distribution of the forces resulting from either internal or external pressure, and rendering them less liable to result in injury to the 35 tank.

A further object is to eliminate the use of rivets in the construction of the body of the tank and in the securing of the splash plate structure thereto, whilst obtaining a 40 tank and splash plate structure wherein the application of internal forces resulting from a pressure therewithin have a tendency to render more effective the supporting of the body of the tank by the splash plate structure 45 and of the splash plate structure by the body of the tank; and a still further object of the invention is to provide a splash plate structure within the tank without riveting or similar positive connection there- 50 to in a manner ensuring the said splash plate structure against shifting or similar disturbance within the said tank.

Still further objects subsidiary to or resulting from the aforesaid objects, or from 55 the construction or operation of the invention as it may be carried into effect, will

become apparent as the said invention is hereinafter further disclosed.

In carrying the said invention into effect I may provide a sheet metal tank of elliptical configuration in cross section, the ends whereof are welded or soldered into position and the body of which is provided with a series of annular outwardly distended corrugations; and longitudinally disposed 60 splash plates within the said tank supported by transverse elliptical partitions, the edges of which partitions extend into and are held by the said annular corrugations in such manner that the said corrugations effectively 65 prevent the movement of the said partitions and consequently of the splash plates, and whereby, further, the said partitions effect a distribution of forces resulting from internal or external pressures applied to the 70 body of the tank in a manner preventing 75 undesired distortion of the tank by such forces.

All of which is more particularly described and ascertained hereinafter, by way 80 of example, having reference to the accompanying drawing, wherein—

Figure 1 is a side elevation, partly broken away, of a gasoline tank embodying the 85 said invention;

Figure 2 is a plan of the same, also partly broken away to show the interior construction;

Figure 3 is a transverse section, taken 90 on the line 3^x—3^x of Figure 2; and

Figure 4 is a diagrammatic sectional view 95 of the wing of an aeroplane, illustrating the adaptability of the said tank thereto.

Similar characters of reference indicate 100 similar parts in the several figures of the drawing.

The tank is illustrated as formed from a sheet of metal 1 bent to a tubular elliptical form and joined at 2, such as by welding 105 3, the minor axis thereof being vertical when the tank is laid upon its side and the ends 4 and 5 of the tank being also elliptical and provided with outwardly turned flanges 6 and 7 which are inserted into the said ends 110 of the tank. 8 and 9 indicate the welding 105 which may be employed for the securing of the end plates in position. The welding, where such method of sealing the ends of the plate 1 and the joints between the end plates 4 and 5 and the plate 1 is employed, 110 may be effected electrically or in any other convenient manner.

Within and at intervals in the length of the tank are arranged partitions 10 and 11, the said partitions being also elliptically shaped and provided with openings 12 to afford communication between the compartments formed by the said partition, the said openings being preferably so disposed throughout the partitions that the said partitions may act as splash plates for the interference of flow of gasoline or other liquid in the tank freely from end to end thereof to such an extent as would be objectionable, and to break up the body of liquid in a manner preventing the violent tossing of the same from end to end in the tank when the same is subjected to motions which would ordinarily have that effect.

The said partitions are of somewhat greater dimensions than the general cross sectional dimensions of the body of the tank, and for their accommodation the said tank is provided with annular ribs or corrugations 13 and 14, outwardly distended to form annular recesses on the inner wall of the said tank into which the margins 15 and 16 of the said partitions extend, these margins being in the form of arcuate flanges or hollow rims nesting within the recesses formed by the said corrugations 13 and 14 respectively.

Several important results are secured by this arrangement of the partitions within the tank as will now be explained. In the first place, the engagement of the partitions by the corrugations effectively secures the said partitions in position without necessitating riveting, welding or further means of attachment; the presence of the partitions in this manner ensures the distribution of strains tending to distort the body of the tank, such as the strain resulting from internal pressures when the device is used as a pressure tank, the tendency of such pressure to expand the tank in the direction of its minor axis simply resulting in a tendency to reduce the major axis thereof which is resisted by the partitions with a consequent firmer engagement of the wall of the tank about the ends of the said partitions. Thus the effect of such pressure, instead of reducing or tending to reduce the support of the walls of the tank by the partitions, effects a closer binding of the same together whereby, unless the pressure be so much greater than that for which the tank is designed that an actual disruption of the walls thereof would take place, no objectionable distortion of the tank would result from the internal pressure. Incidentally, of course, the described reinforcement of the tank by the said partitions resists the damaging thereof by externally applied pressures or strains as will be quite obvious.

It will be further noted that the flanging of the margins of the partitions and the

nesting of the same in the annular corrugations of the tank ensures a substantial bearing surface between the partitions and the body of the tank and also strengthens the partitions very materially. The presence of the corrugations also of itself forms a reinforcement of the tank.

The said partitions are still further strengthened and their usefulness increased by the attachment thereto of splash plates 17, 18 and 19. These are arranged vertically in spaced relation transversely of the tank and are provided with openings 20 functioning in the same manner as the openings 12 of the partitions 10 and 11 to permit flow of the gasoline or liquid transversely of the tank, at the same time break up the body of the liquid to prevent excessive tossing thereof when the motions of the tank would ordinarily result in such action.

The plates 18 extend between the partitions 10 and 11 and are provided with flanges 21 and 22 secured thereto and forming braces for the said partitions which in turn form supports for the said splash plates. Such splash plates, therefore, do not require to be directly secured to the body of the tank and are very effectively and rigidly supported therewithin, any strain upon the splash plates by the liquid within the tank being absorbed by the partitions and distributed throughout the body of the tank thereby. The said splash plates 18 also effect the mutual supporting of the partitions 10 and 11 so that most of the strains to which the said partitions are subjected, particularly those which have a tendency to buckle them, are distributed throughout both of them as will be apparent.

The splash plates 17 and 19 are also provided with flanges 23 and 24 secured to the said partitions 10 and 11 respectively and at their outer ends with recesses 25 and 26 within which are situated transverse channels 27 and 28 secured to lugs 29 and 30 on the said splash plate 17 and 19 respectively.

The end portions of the body of the tank are inwardly ribbed or corrugated at 31 and 32 to provide for the reinforcement thereof and the channels 27 and 28 extend transversely within the tank and in the direction of the major axis thereof into contact with the said corrugations 31 and 32 so that they also resist the reducing of the major axis at the ends of the tank and consequently the expanding of the tank in the direction of its minor axis.

As will be seen from Figure 4 of the drawing, the shape resulting from the construction of the tank in this manner lends itself to utilization in narrow restricted locations such for example as in the wing of an aeroplane, 33 indicating a hollow wing having struts 34 flanking a space or chamber 130

35 within which the tank is situated and secured by supporting means 36 and embracing means 37.

In a tank built upon the lines suggested in the example, no direct attachment is necessitated between the splash plates and the body of the tank and advantage is taken of the said splash plates and their supporting means in the reinforcing of the tank as explained, a minimum number of seams and freedom from rivets or connections in the body of the tank being secured without complicating the structure thereof, and a simple design being maintained capable of easy manufacture and great durability without excessive weight.

Herein, and in the claims appended hereto, the term "elliptical" as applied to the shape of the tank and its partitions is not intended to be read in the technical sense as merely indicating structures in the form of a precise geometric ellipse but to indicate such approximate shape wherein such parts are curved and of greater dimension through one axis than through an axis transverse thereto.

This invention may be developed within the scope of the following claims without departing from the essential features of the said invention, and it is desired that the specification and drawing be read as merely illustrative and not in a limiting sense, except as necessitated by the prior art.

What I claim is:—

35 1. A gasoline tank comprising an elliptic cylindrical body, reinforcing annular corrugations proximate to the ends thereof, a plurality of reinforcing corrugations inter-

mediate the ends of said tank, transverse partitions held by said corrugations, longitudinally disposed splash plates connected and supported by said partitions, splash plates extending from the proximity of the ends of said tank to the adjacent partitions, and bracing means engaging the end corrugation of said tank connecting last named splash plates together.

2. A gasoline tank comprising a splash plate structure including longitudinal splash plates, transverse elliptical partitions to support the latter, a body comprising a shell of metal formed with a plurality of spaced intermediate internal peripheral grooves in which the peripheries of said partition are engaged and said body also formed with end peripheral grooves, elliptical plates closing the ends of said body, and transverse bracing bars at each end of the tank held in said end grooves and adapted to stiffen said splash structure.

3. The combination with a high pressure elliptic tank for aeroplanes formed with closely spaced internal peripheral grooves, and end grooves spaced a short distance from the extreme ends of said tank, of elliptical flanged end partition plates adapted to be engaged within said first named grooves, splash plates secured to said partition plates, bracing bars in the ends of the tank and engaging with said end grooves adapted to stiffen said splash plate structure, and flanged end plates fitted within the extreme ends of the tank, and welded thereunto.

In testimony whereof I affix my signature.

WILLIAM B. STOUT.
